(57) **CLAIM**

The ornamental design for a cordless screwdriver, as shown and described.

DESCRIPTION

FIG. 1 is a front perspective view of a cordless screwdriver showing my new design;

FIG. 2 is a side view thereof;

FIG. 3 is the opposite side view of FIG. 2;

FIG. 4 is a top view thereof;

FIG. 5 is a bottom view thereof;

FIG. 6 is a front view thereof;

FIG. 7 is a rear view thereof;

FIG. 8 is a front perspective view of a alternate embodiment of a cordless screwdriver showing my new design without any writings or logo thereon;

FIG. 9 is a side perspective view thereof;

FIG. 10 is the opposite side view of FIG. 9;

FIG. 11 is a top view thereof;

FIG. 12 is a bottom view thereof;

FIG. 13 is a front view thereof; and,

FIG. 14 is a rear view thereof.

The broken line showing of environmental structure is for illustrative purposes only and forms no part of the claimed design.

The names Bosch and IXO displayed on the cordless screwdriver are trademarks owned by Robert Bosch GmbH.
